UNITED STATES PATENT OFFICE.

CHARLES EDGAR LORD, OF BOSTON, MASSACHUSETTS.

CASH INDICATOR AND REGISTER.

SPECIFICATION forming part of Letters Patent No. 398,898, dated March 5, 1889.

Application filed October 11, 1888. Serial No. 287,902. (No model.)

To all whom it may concern:

Be it known that I, CHARLES EDGAR LORD, a citizen of the United States, residing at Boston, in the county of Suffolk and Commonwealth of Massachusetts, have invented a new and useful Improvement in Cash-Registers, of which the following is a specification.

The object of my invention is to provide means whereby it is made more difficult than it has heretofore been to make a false registration.

My invention is illustrated in the accompanying drawings of certain portions of a cash-register, and in which—

15 Figure 1 is a view seen when looking upwardly at the under edges of the registering-keys of a portion of a cash-register whose keys are arranged in sets having nine keys in each set. Fig. 2 is an elevation, partially 20 in section, of the line 2 2 of Fig. 1; and Fig. 3 is an elevation similar to that shown in Fig. 2, but showing some of the keys depressed from their normal position.

Similar letters of reference refer to similar 25 parts in all of the views.

In the drawings, *a a* represent portions of the frame of a cash-register, to which are pivoted upon the rod *b* the keys *c c c*. Each 30 of the keys *c* is provided with projections *d*, which engage with the bars *i* and *j* upon the key-coupler *l*, which is made up of said bars *i* and *j* and the arms or levers *h h*. The key-coupler *l* is pivoted upon the arms *e e*, which are in turn pivoted upon the rod *b* or 35 other suitable pivot upon the frame of the machine. The arms *e e* are shown as connected by the stop-bar *k*, thus making the key-coupler support *l* sufficiently rigid. The arms *e e* are shown as held by the springs *f f* 40 against the stops *g g* upon the frame, although a suitably-arranged weight may be arranged to take the place of said springs when it is desirable to do so.

In Fig. 2 the keys and key-coupler *l* are 45 shown in their normal position, ready for a registration to be made. When the operator displaces one or more of the keys *c*, as shown in Fig. 3, the projections *d* upon said displaced keys will come in contact with the bar *i* and partially rotate the key-coupler *l* upon the pivots *n*. When this rotation takes place,

the bar *j* is carried over the catches *m* upon the projections *d* upon those keys *c* that have been displaced, thereby locking all the depressed keys together and forcing all of 55 said keys to complete their forward motion whenever any one of said keys is completely depressed, the arms *e e* yielding to allow said complete depression to take place. When said keys have completed their forward motion, as above described, and the downward pressure upon said keys is removed, or the pressure of the projections *d d* upon the bar *i* is released, the weight of the bar *j* will cause 60 said bar to fall away from the catches *m m* 65 against the bar *k*, thus uncoupling all keys. If for any reason the weight of the bar *j* does not act as above described immediately after registration, said keys would remain coupled together by the bar *j* until the lever *e* had returned to its normal position, after which the 70 keys would continue their backward motion and force the bar *j* off of the catches *m m* by means of the inclined bearing-surfaces of said catches *m m*, as seen in Fig. 2. It will thus 75 be seen that the keys will be uncoupled after registration and before said keys have returned to their normal positions. The bar *j* is so adjusted with respect to the projections *d d* that it will, when in use, swing under any 80 of the catches *m m* upon said projections *d d*, when said projections are in their normal positions; but above the catches *m m* are projections *d d*, which are on the keys that are slightly displaced from their normal position, 85 as shown in Fig. 3.

It will thus be seen that when my improvement is applied to a keyed cash-register it is necessary that all the keys which are displaced from their original position must move 90 together in their forward or registering motion, even if the finger of the operator should slip from any of said keys.

I have omitted from my drawings and description all reference to any registering mechanism or key-locking mechanism, since such mechanism is not thought to be necessarily shown or described, in order that persons skilled in the art of making cash-registers should understand this my present improvement and be able to apply the same to cash-registers.

I do not desire to limit myself in the use of my improvement to any particular style or type of cash-register, as it is applicable to a great many such types of register; nor do I desire to limit myself to the especial form and arrangement of the parts which are illustrated, since such form and arrangement are necessarily modified to suit the requirements of different registers now well known.

10 What I claim as new, and desire to secure by Letters Patent, is—

1. In a cash-register, the combination, with the registering-keys, of the key-coupler adapted to couple the displaced keys together during their registering motion, substantially as described, and for the purposes specified.

2. In a cash-register, the combination, with the registering-keys, of the key-coupler adapted to couple the displaced keys together during their registering motion, and to uncouple said keys from each other after the registration has been completed, substantially as described, and for the purposes specified.

3. In a cash-register, the combination, with the registering-keys, each adapted to engage with a key-coupler, of the movable key-coupler support and the key-coupler mounted thereon and adapted to engage with displaced

registering-keys during their registering motion, substantially as described, and for the purposes specified.

4. In a cash-register, the combination, with a set of registering-keys, of a key-coupler support pivoted to a suitable support, and the key-coupler pivoted upon said key-coupler support and engaging with displaced registering-keys during their registering motion, substantially as described, and for the purposes specified.

5. In a cash-register, the combination, with the pivoted registering-keys, each provided with the projection *d*, of the key-coupler support pivoted to a suitable support and held toward said keys by suitable means, and the key-coupler pivoted on said key-coupler support and engaging with the projections *d* on the displaced registering-keys during their registering motion, substantially as described, and for the purposes specified.

In testimony whereof I have hereunto set my hand in the presence of two subscribing witnesses.

CHARLES EDGAR LORD.
